CLAIM

The ornamental design for a fire extinguisher holder, as shown and described.

DESCRIPTION

FIG. 1 is a right front perspective view of a fire extinguisher holder showing our new design.

FIG. 2 is a front elevational view thereof.

FIG. 3 is a back elevational view thereof.

FIG. 4 is a right side elevational view thereof, the left side elevational view being a mirror image of the right side elevational view.

FIG. 5 is a top plan view thereof; and,

FIG. 6 is a bottom plan view thereof.

The broken lines shown in the drawings represent visible environmental structure or unclaimed portions of the structure of the fire extinguisher holder, and form no part of the claimed design.
